United States Patent Office

Des. 225,233

Patented Nov. 28, 1972

225,233

TELEPHONE OPERATOR'S SERVICE CONSOLE

George M. Janda, Westchester, Ill., assignor to GTE Automatic Electric Laboratories Incorporated, Northlake, Ill.

Filed Jan. 11, 1971, Ser. No. 105,770

Term of patent 14 years

Int. Cl. D14—02

U.S. Cl. D26—5

FIG. 1

FIG. 2

FIG. 3

FIG. 1 is a front, left-side and top perspective view of a telephone operator's service console, showing my new design;

FIG. 2 is a front elevational view;

FIG. 3 is a rear elevational view;

The dominant features of my new design are shown in the drawings.

I claim:

The ornamental design for a telephone operator's service console, as shown.
